1 Claim. (Cl. 141—286)

The present invention relates to gas fueled cigarette lighters, and in particular to a valve mechanism for introducing gaseous fuel to the lighter reservoir.

Valves, for filling reservoirs with liquified gas, having a separate and distinct passageway for (1) the introduction of fuel to the reservoir and (2) the escape of air and excessive fuel from the reservoir to the atmosphere, are well known in the art. Valves of this type, having separate "inlet" and "outlet" passageways to and from the lighter reservoir are described, for example, in U.S. Patent Nos. Re. 24,163; 2,882,940; 3,093,166; and 3,115,907. Although the valves disclosed in the above patents are satisfactory from a functional standpoint, the manufacture of the separate passageways is relatively complicated and obviously results in an increase in the manufacturing costs of the valves.

Recent attempts to eliminate separate and distinct "inlet" and "outlet" passageways have resulted in the utilization of interconnections for refill vessels and lighter reservoirs, such as described in U.S. Patent Nos. 3,146,808 and 3,148,712, for example. The resulting "pseudo-single passageway" valve constructions are achieved with the use of elongated and/or deformed top portions of the refill vessels, the remaining "partially separate" inlet and outlet passageways providing only partial relief from the conventional "completely" separate passageway constructions long commonplace in this industry.

The present invention envisions a filler-valve construction in which a single orifice defines both the inlet and outlet passageways eliminating the "complete" separation of passageways such as is present in Patent Nos. Re. 24,163; 2,882,940; 3,093,166; and 3,115,907 or "partial" separation such as is present in Patent Nos. 3,146,808 and 3,148,712. The present invention, then, concerns valves for refilling lighter reservoirs with liquified gas wherein a "true" single passageway is utilized for the (1) introduction of gaseous fuel into the reservoir and (2) escape of air and excessive fuel from the reservoir to the atmosphere.

Although the utilization of a "single" passageway filler-valve obviously reduces manufacturing costs, such a valve structure will only be commercially acceptable if the refilling operation is smooth and safe. Prior filling valves, such as described in the above patents, have utilized separate inlet and outlet passageways because of the assumptions that (1) the pressure in the filler valve itself is constant throughout and greater than the pressure in the lighter reservoir and (2) the pressure in the lighter reservoir is constant and greater than the atmospheric pressure. Careful study and experimentation, however, has revealed that the pressures both in the filler valve and in the reservoir are not constant. In fact, these pressures vary in accordance with the relative positions within the valve and reservoir. Guided by the above discovery, and desirous of establishing the necessary pressure relationships to ensure the smooth flow of fuel, it was further discovered that a "jet" stream of released butane might establish within the valve an independent inlet path of gaseous fuel without the necessity of separating same from the outward flow of air and excessive fuel. Furrows were designed to cause the fuel discharging from the refill bomb to "jet" into the reservoir thus eliminating

2

the necessity of utilizing structure defining a separate inlet passageway for the gaseous fuel.

Accordingly, it is an object of the invention to provide in a gas fueled lighter an improved filler-valve mechanism.

Another object of invention is to provide in a gas fueled lighter an improved filler-valve comprising a single passageway for both the inlet of gaseous fuel and the outlet of air and excessive fuel from the reservoir.

Yet additional objects of invention will become apparent from the ensuing specification and attached drawings wherein:

FIG. 1 is a side elevation in section of the filler-valve in closed position; and

FIG. 2 is a side elevation in section of the filler-valve in open position.

In the filler-valve construction, as illustrated in FIGS. 1 and 2, the lighter casing is generally indicated by 100. The filler-valve comprises a stationary outer valve member 112 and a movable inner valve member 114 mounted within outer valve member 112 in rectilinear sliding relationship. The stationary outer valve member 112 is secured to wall 100 of the lighter casing and held in spaced relationship thereto with rubber sealing member 113. Stationary outer valve member 112 includes upper cylindrical sleeve portion 118 and lower cylindrical member 120 threadedly attached thereto. Movable inner valve member 114 includes an upper portion 130 and a lower portion 141 intersecting to form at the middle of movable inner valve member 114 a valve seat 136 which supports rubber sealing means 138. Upper portion 130 of movable inner valve member 114 terminates at the top thereof in a dish-plate like seat 150 having an opening 151 therein. A rubber sealing member 152 having a small opening 153 therein, which is in connection with opening 151, is located on seal 150. In the bottom of lower cylindrical member 120 is located opening 126 through which movable inner valve member 141 may slide up and down freely in accordance with the contact pressure applied to dish-plate like seat 150 by the top portion 160 of fuel containing bomb 162 against spring 128, during filling.

The operation of the filler-valve construction of FIGS. 1 and 2 is initiated when the top portion 160 of refilling bomb 162 is depressed against the dish-plate like seat 150 causing movable inner valve member 114 to move downwardly to open valve seat 136 against the pressure of spring 128 simultaneously causing the fuel in the bomb to pass through small holes 151 and 153 and then to "jet" into the chamber 111 surrounded by the inner walls of upper cylindrical sleeve portion 118 and lower cylindrical member 120 respectively. Note that the top portion 160 of bomb 162 is received by the dish-plate like seat 150 and is not inserted in the inner space limited by the walls of upper cylindrical sleeve portion 118 and lower cylindrical member 120. Fuel, being jetted into chamber 111, runs into the reservoir of the lighter body through windows 122 on the wall of lower cylindrical member 120. Air and exhaust fuel pass inwardly through windows 122 into chamber 111, without being separated by any artificial means from the in-coming jet of fuel, and then escapes into the atmosphere passing the gap between dish-plate like seat 150 and the inner walls of upper cylindrical sleeve portion 118.

Manifestly, various changes in construction and substitution of parts may be employed without departing from the spirit and scope of invention, as defined in the subjoined claim.

I claim:

An arrangement for filling a lighter tank containing a fuel reservoir with liquified gas continued in a gas supply bomb, comprising in combination;

(A) fuel charging means carried by said lighter tank and affording simultaneous escape of gas from said reservoir and charging of said reservoir with liquified gas under pressure, said fuel charging means including

(1) an outer valve member having a top wall and side walls fixed with respect to said tank, said outer valve member including a passageway located near the top thereof and communicating with the atmosphere at said top wall, at least one window located in said side walls thereof and communicating with said reservoir to serve as a passageway for both the charging of fuel into said reservoir and the escape of air and excess fuel therefrom, and valve seat means;

(2) an inner valve member mounted to move within said outer valve member between open and closed positions and including a first rod portion terminating at the top thereof in a dish-plate like seat for engagement with said gas supply bomb, said dish-plate like seat being located within said passageway of said outer valve member at the upper portion of said side walls and in close proximity to said top wall of said outer valve member, said dish-plate like seat containing a small vertical aperture therein for jetting fuel vertically downward along the outside of said first rod portion of said inner valve member into and through said window of said outer valve member, an intermediate shoulder portion extending outwardly from said first rod portion and spaced downwardly along said first rod portion a distance from said dish-plate like seat approximately equal to the distance between said top wall of said outer valve member and

said valve seat means of said outer valve member and containing a transverse surface resting in engageable relationship with said valve seat means of said outer valve member when said inner valve member is in closed position, and a second rod portion extending below said intermediate shoulder portion;

(B) mounting means affording substantially rectilinear sliding movement of said inner valve member with respect to said outer valve member in moving between said open and closed positions; and

(C) spring means urging said inner valve member towards said closed position.
